UNITED STATES PATENT OFFICE.

WILLIAM S. G. BAKER, OF BALTIMORE, MARYLAND.

CAR-AXLE BOX.

SPECIFICATION forming part of Letters Patent No. 276,210, dated April 24, 1883.

Application filed February 27, 1883. (No model.)

To all whom it may concern:

Be it known that I, WILLIAM S. G. BAKER, of Baltimore, in the county of Baltimore and State of Maryland, have invented certain new and useful Improvements in Car-Axle Boxes, of which the following is a specification, reference being had to the accompanying drawings, in which—

Figure 1 is an end elevation of an axle-box and adjacent parts as if in position under a car. Fig. 2 is a vertical section on the line 2 2 of Fig. 1. Fig. 3 is a side elevation of the box, showing one car-spring in elevation, and Fig. 4 is a view showing on the right a face view of one-half of an annular, flanged, and recessed metallic axle-plate, and on the left a face view of one-half of an annular projection of the car-wheel.

Referring to the letters on the drawings, A indicates an axle; B, a wheel; C, an axle-box; D, a brass bearing; E, a suspension-link; F, a grooved iron shoe or washer supported by the link, and upon which the spring-carriage G rests; H, car-springs; I, spring-bolts, and K a beam making part of a car-frame to which the spring-bolts are secured. All of these parts, so far as described, are of ordinary construction, and are only referred to by way of pointing out what is old, the better to distinguish what I deem to be new, which I will now describe.

First. Heretofore the spring-bolts I, which depend from the beam K in connection with this class of boxes and have to sustain the strain of the swaying of the car-body, have been inadequately braced, and it has been found desirable to strengthen them by an improved means of bracing. Accordingly I have designed a peculiar bracket-brace, L, provided with a central aperture, so that it will slip over the outer end of the axle-box, and also provided with bent arms M, extending under the springs, and having holes to receive the lower ends of the spring-bolts. This brace is secured to the outside of the beam K by bolts or screws in any suitable way, and serves to stay the lower ends of the spring-bolts, while it accommodates the axle-box and gives a better finish to the car. I prefer to make it, as illustrated, in one piece; but it could be made in two parts;

or two independent braces, one on each side of the box, reaching to the lower end of each spring-bolt, might be employed without departing from the substance of my improvement, the main point being to provide means connected with the beam or car-frame for bracing or staying the lower ends of the spring-bolts. I do not confine my invention to the particular mode illustrated of connecting or fastening the lower ends or bent arms of the brace with the lower ends of the spring-bolts; but any ordinary or suitable means may be employed, although a screw-nut, N, affords a good fastening.

Second. I provide the box C with an opening at the top, through which the forked key O can be put in place to fit in the annular recess in the end of the axle. This opening I cover by a cap, P, resting or fulcrumed at its inner end by means of the bent end or lug X on the top of the box, as well illustrated in Fig. 2, and held in place by the bolt or bolts Q, which serve, when screwed home, to bring the outer end of the cap down upon the top of the outer vertical wall of the box and make an oil-tight joint. The brass bearing D is inserted from the back end of the box.

Third. I provide an annular plate, R, to encircle the axle between the box, and an annular projection, S, upon the car-wheel. This plate is provided with recesses, as indicated in Fig. 4, and, say, for example, eight in number, more or less. The annular projection upon the wheel is provided with pins or lugs S'—say four in number—to fit into alternate recesses in the plate. The remaining recesses in the plate contain suitable coil-springs, T, bearing upon the bottoms of their recesses in the plate at one end, and upon the face of the annular projection S at the other end. This plate is provided with segmental flanges U, and between it and the box is a suitable annular leather washer, V.

From this description of the structure and arrangement of the parts it will be seen that the springs will tend to brace the plate against the leather washer and the washer against the inner end of the box. The pins within the recesses will serve to turn the plate, and with it the washer. The metal plate and washer turn-

ing with the axle are made to fit tightly upon it. The result of this structure is to produce an oil and dust tight joint affording thorough protection to the journal of the car-axle and 5 the brass bearing within the box.

Having thus described my improvements, what I claim, and desire to secure by Letters Patent of the United States, is—

1. The combination, with the beam K and 10 the spring bolt or bolts I, of a brace, L, rigidly secured to the beam and extending down past the axle-box, and rigidly secured to the lower end of one or more of the spring-bolts, substantially as and for the purpose set forth.
- 15 2. The axle-box provided with the opening at the top, in combination with the cap P, fulcrumed at its inner end by means of the lug X on top of the box, and screw-bolts Q, for bringing the outer end of the cap down upon the 20 wall of the box to form a tight joint, substantially as set forth.

3. In combination with the axle-box and wheel, the annular plate R and washer V, constructed and arranged to revolve with the wheel, substantially as and for the purpose set 25 forth.

4. The combination of the wheel provided with the annular projection S and pins S', the annular recessed plate R, carrying the springs T, the washer V, and axle-box C, constructed 30 and arranged substantially as and for the purpose set forth.

In testimony whereof I have hereunto subscribed my name this 19th day of February, A. D. 1883.

WM. S. G. BAKER.
